UNITED STATES PATENT OFFICE.

CHARLES A. CHANNELL, OF CHICAGO, ILLINOIS.

DESIGN FOR A MOP.

52,908.

Specification for Design.

Patented Jan. 28, 1919.

Application filed September 27, 1915. Serial No. 52,966. Term of patent 14 years.

To all whom it may concern:

Be it known that I, CHARLES A. CHANNELL, a citizen of the United States, and residing in Chicago, in the county of Cook and State of Illinois, have invented a new, original, and ornamental Design for Mops, of which the following is the specification, reference being had to the accompanying drawings, forming a part thereof.

In the drawings:

Fig. 2 is a view in elevation, thereof.

I claim:

The ornamental design for a mop as shown.

CHARLES A. CHANNELL.
